GONIOMETER

Stanley H. Gartman and Edward F. Meyers, Roslyn Heights, and Tore Anderson, Brookville, N.Y., assignors to Budd-Stanley Co., Inc., Syosset, N.Y., a body corporate of New York

Filed Aug. 20, 1964, Ser. No. 81,383

Term of patent 14 years

(Cl. D52—6)

FIG.-1

FIGURE 1 is a plan view of the goniometer according to the invention;

FIGURE 2 is an isometric view of the goniometer according to the invention; and

FIGURE 3 is a side elevational view of the goniometer.

The essential features of the design reside in the portions shown in full lines. Some of the indices have been omitted from FIGURE 2 for convenience of illustration.

We claim:

The ornamental design for a goniometer, as shown and described.
